UNITED STATES PATENT OFFICE.

CHARLES T. LITCHFIELD, OF ROSALIA, AND RALPH D. MCKAY, OF TACOMA,
WASHINGTON.

SELF-BALANCING AEROPLANE.

1,011,354.

Specification of Letters Patent. Patented Dec. 12, 1911.

Application filed May 15, 1911. Serial No. 627,275.

To all whom it may concern:

Be it known that we, CHARLES T. LITCHFIELD, of Rosalia, in the county of Whitman and State of Washington, and RALPH D. MCKAY, of Tacoma, in the county of Pierce and State of Washington, citizens of the United States, have invented a certain new and useful Improvement in Self-Balancing Aeroplanes, of which the following is a full, clear, and exact description.

The object of this invention is to provide an airship of the aeroplane, biplane type, which will for all practical purposes be self-balancing.

The main body of the apparatus comprises a biplane with a substantially central backbone, in which the propeller is mounted in an adjustable manner at the front of the body, and vertical and horizontal rudders are arranged at the end of the backbone, and horizontal balancing planes arranged at opposite ends of the body and connected with an automatically operating adjusting mechanism connected with the main body or backbone in such way that there may be a relative movement of the adjusting mechanism as the body tilts sidewise in order to adjust the balancing planes correspondingly.

The invention consists of these features and others collateral thereto in the control of the movements or flight of the machine.

In the accompanying drawings, illustrating the invention, in the several figures of which like parts are similarly designated, Figure 1 is a top plan view. Fig. 2 is an elevation of the adjusting mechanism detached and with the body level, and Fig. 3 is a similar view of said mechanism with the body tilted. Fig. 4 is a front elevation. Fig. 5 is a rear elevation. Fig. 6 is a side elevation. Fig. 7 is a plan view on a larger scale, of one form of propeller adjusting mechanism, and Fig. 8 is a side elevation thereof.

The planes 1 and 2 of the main body may be of any usual or approved construction, comprising posts 3 and stringers 4, and suitable covering, with suitable stays 5; and the backbone or tail likewise may consist of suitable posts 6, stringers 7, and stays 8.

The main frame or body carries any suitable motor 9, having a shaft 10 provided with a sprocket wheel 11, connected by a transmission device 12 with a sprocket wheel 13 on the propeller shaft 14, and said pro-

peller shaft has a bearing in the frame 15 in which is mounted the yoke 16, carrying a stub shaft 17 on which the propeller 18 is directly mounted, and this stub shaft is connected by a universal joint 19 with the shaft 14 in such way that the propeller may be tilted to any desired angle. The tilting mechanism may comprise a toothed segment 20 meshing with a worm 21 on the shaft 22 reaching back through the main frame, and provided with a hand-wheel 23 within convenient reach of the aviator. The invention, however, is not limited to any of these details, and they may be altered at pleasure.

At the ends of the main frame are mounted the horizontal planes 24, herein referred to as the "balancing" planes, otherwise ailerons or warping wings or devices, and these balancing planes are connected by a cord or other suitable medium with the ends of the adjusting mechanism, so that the balancing planes are tilted in accordance with the relative inclination of the main body and the adjusting mechanism.

The mechanism for adjusting the balancing planes in accordance with the tilt of the aeroplane, comprises a rigid frame 25, fixed to the bottom of the main body and having pivoted in it two pendulums 26 of like construction, and these pendulums have a loose connection with a rod 27 which is connected at opposite ends to the endless cord 28 which in turn is connected to the balancing planes at opposite ends of the body. A spring 29 is arranged upon the rod 27 between the pendulums, and the pendulums are held substantially parallel against the thrust of the spring by means of fixed buttons 30 on the rod. Each pendulum is supplied with a quadrant, sector or bell-crank lever 31, and these quadrant levers are connected by links 32 with a portion of the rigid frame. Each quadrant lever has a latch 33 extending upwardly through a guide 34 and supplied with a contact face 35 for co-operation with the respective buttons as the body tilts sidewise. As shown in Fig. 2, the latches are out of contact with the buttons when the machine is on a level, and when the machine is tilted, the pendulum on the downwardly inclined side will swing out and its quadrant lever will be actuated so as to throw the latch into contact with the adjacent button and thereby draw upon that side of the end 110

less cord 28, so as to effect an adjustment of the balancing planes. The companion pendulum is unaffected and remains in its original position.

- 5 The adjusting mechanism may be put anywhere under the body, in the center, or with one of the pendulums on each side of the center, and each pendulum is limited in its action, swinging only through a short arc 10 of a circle, or in other words, through one half of the arc of the circle traversed by the two. This provision is made in order to overcome the oscillation of the pendulums when the machine comes to a level.
- 15 It will be understood that the latches normally tend to engage the buttons when the aeroplane tilts, the latch on the downwardly inclined side receiving a vertical motion through the action of the link and quadrant 20 and rising into position behind the button and thereby imparting motion to the balancing planes through the endless connecting cord 28, as already indicated. It will be observed that the endless connecting cord will 25 receive motion from one pendulum only at a time.

As clearly indicated in Figs. 2, 4 and 5, the adjusting mechanism is normally inactive when the aeroplane is level. As the 30 machine comes to a level after tilting, the latch is thereby thrown out of contact with the button and the pendulum comes to a rest at a definite point, and cannot swing about the center. A pair of pendulums is necessary 35 in order to obtain a cessation of movement of the balancing planes when none is required. A pair of pendulums also avoids the constant oscillation that a single pendulum would have, and, consequently, avoids 40 the continual adjustment of the balancing planes that would be incident to the use of a single pendulum.

It will be observed that each pendulum operates in one direction only to effect movement 45 of the balancing planes operating cord.

The operation has been described with respect to the right hand pendulum, but what has been said of that applies equally to the left-hand pendulum when the machine is 50 tilted downwardly in that direction.

By the term "rod" as applied to the device 27 and the term "cord" as applied to the device 28, we do not intend to limit our invention to any particular material for 55 forming the endless or other connection between the balancing planes 24 and the pendulums, and we use the term "endless" merely as a convenient designation to indicate that these parts are so connected that 60 both planes are operated simultaneously and complementally by the respective pendulums as they respectively swing under the inclination of the machine.

36 is a vertical rudder placed at the end 65 of the backbone or tail, and connected by

cords 37 with the foot-lever 38 within convenient reach of the aviator. The tail also has a pair of horizontal rudders 39 mounted to work together and connected by a cord or other medium 40 which extends to a lever 70 41 mounted on the main frame within reach of the aviator.

If desired, a fixed wheel 42 may be mounted beneath the backbone and fixed wheels 43 may be mounted beneath the body for supporting the machine when it is upon the ground and for starting and landing purposes.

The propeller may be tilted backward or forward relatively to the main body in order, 80 respectively, to elevate the machine or to cause it to descend.

In order to prevent too sudden descent when gliding to the ground, and in order to stop the machine within a short distance 85 after reaching the ground, we provide the brake-curtains 44, arranged on opposite sides of the aviator, within the main frame, and these brake-curtains may be arranged upon vertical rollers, substantially like the ordinary 90 spring curtain roller, acting to roll up the curtains, the unrolling being effected by cords connected therewith and brought into convenient reach of the aviator.

In starting the machine from the ground, 95 the propeller may be tilted, point upward, and the horizontal rudders 39 may be given a similar tilt, and then the machine run a short distance on the ground.

It will be noted that in the operation, the 100 balancing planes 24 at opposite ends of the main frame, are simultaneously tilted in opposite directions and the effect of this action is to keep the machine balanced.

What we claim is:—

1. A self-balancing aeroplane, having a main body, horizontal balancing planes arranged at the extremities of the main body, a pair of pendulums, and means to connect the balancing planes and the pendulums, so that said balancing planes will be adjusted in accordance with the motions of the main body, and means to compel the pendulums to swing away from the center of motion in one direction and restrain them from passing such center in the opposite direction.

2. In an aeroplane, the combination of a main body, balancing planes at its opposite ends, and an automatically operated adjusting mechanism for said balancing planes, 120 consisting of an endless cord connecting said balancing planes, and two pendulums hung in a common frame fixed to the aeroplane, said pendulums having independent connection with the endless cord and rendered active independently of one another as the aeroplane tilts toward them respectively.

3. In an aeroplane, a body having balancing planes at its opposite ends and an endless operating cord connecting them, in 130

- combination with a pair of pendulums movable with relation to the aeroplane, a rigid frame on the aeroplane in which said pendulums are hung, means for connecting the 5 pendulums independently with their frame at a point below their axes, and latches pivotally connected with said connecting means and adapted to be moved into operative contact with the endless operating cord as the 10 aeroplane is tilted toward one or the other.
4. In an aeroplane, the combination with a body having balancing planes at its ends, an endless operating cord, a pair of pendulums connected at one end with said operating 15 cord loosely, and means carried by said pendulums to independently connect said pendulums rigidly with the operating cord as the aeroplane is tilted toward the said pendulum.
- 20 5. In an aeroplane, the combination with a body having balancing planes at its ends, an endless operating cord, a pair of pendulums connected at one end with said operating cord loosely and yieldingly, and means 25 carried by said pendulums to independently connect said pendulums rigidly with the operating cord as the aeroplane is tilted toward the said pendulum.
6. In an aeroplane, the combination of a 30 body having balancing planes at opposite ends, and an endless operating cord connecting said balancing planes, of independently pivoted pendulums connected with the endless operating cord loosely, a carrier in 35 which said pendulums are suspended from the body of the aeroplane, a latch mounted upon each pendulum, a sector lever pivoted in each pendulum and carrying the latch, and a link for connecting the sector lever 40 with the pendulum carrier, the construction and arrangement being such that only that pendulum moves which is next to the downwardly inclined side of the aeroplane relative to its center of motion, while the other 45 pendulum remains quiet and unaffected.
7. In an aeroplane, the combination of a body having balancing planes at opposite ends, and an endless operating cord connecting the said balancing planes, of independently pivoted pendulums connected with the 50 endless operating cord loosely, a carrier in which said pendulums are suspended from the body of the aeroplane, buttons on the endless operating cord outside of the pendulums, a latch mounted upon each pendulum, 55 a sector lever pivoted in each pendulum and carrying the latch, and a link for connecting the sector lever with the pendulum carrier, the construction and arrangement being such that only that pendulum moves 60 which is next to the downwardly inclined side relatively to the center of motion of the aeroplane, while the other pendulum remains quiet and unaffected, the latch of the swinging pendulum engaging the button on 65 the endless operating cord and serving to shift the cord and both balancing planes thereby to restore and maintain the proper level of the aeroplane.
8. In a self-balancing aeroplane, means 70 for propelling it, an automatically operating duplex pendulum arranged beneath the aeroplane, and balancing planes arranged at opposite ends of the body and connected 75 with the duplex pendulum so as to partake of the oscillations of the aeroplane, and means to compel the pendulum to swing away from its center of motion and restrain it from swinging beyond such center in the opposite direction. 80

In testimony whereof, we have hereunto set our hands.
